UNITED STATES PATENT OFFICE.

WELMAN B. McCARLEY, OF COLUMBUS, OHIO.

FLYING-MACHINE.

1,133,984.

Specification of Letters Patent. Patented Mar. 30, 1915.

Application filed November 26, 1913. Serial No. 803,278.

To all whom it may concern:

Be it known that I, WELMAN B. McCARLEY, a citizen of the United States, residing at Columbus, in the county of Franklin and State of Ohio, have invented new and useful Improvements in Flying-Machines, of which the following is a specification.

This invention relates to flying machines, and its object is to provide a machine of the aeroplane type having a novel construction and arrangement of supporting surfaces, propelling, steering and controlling devices, whereby greater efficiency of operation and control in flight are obtained and a higher degree of safety secured.

The invention consists of the features of construction, combination and arrangement of parts hereinafter fully described and claimed, reference being had to the accompanying drawings, in which:—

Figure 1 is a top plan view, with the upper main supporting plane removed, of a flying machine embodying my invention. Fig. 2 is a side elevation of the same. Fig. 3 is a vertical longitudinal section. Fig. 4 is a front elevation of the machine. Fig. 5 is a plan view of one of the rear revolving lifting and propelling planes. Figs. 6 and 7 are longitudinal sections thereof. Fig. 8 is a sectional elevation of a portion of the drive gearing associated therewith. Fig. 9 is a similar view of a portion of the drive gearing associated with one of the forward revolving lifting and propelling planes. Fig. 10 is a detail longitudinal section through one of the pivoted wings of the supporting surface and shutter associated therewith. Fig. 11 is a diagrammatic perspective view of the revolving planes, propelling and steering gearing, omitting the revolving planes at one side of the machine. Fig. 12 is a similar view showing the means for adjusting and controlling one of the pivoted wings and its shutter.

In the practical embodiment of my invention, I provide a suitable car or body and launching and alighting base, which may be in the form of a boat-shaped structure or nacelle, provided with suitably cushioned wheels and adapted to serve as a hydrofoil, if desired. Rising from the said car or body is an upright frame structure 3, composed of metallic tubing or other suitable frame elements, properly tied together and braced. The several parts of the upright frame and elements of the superstructure

may be further braced by stay wires 4, in the usual manner. The upright frame structure 3 is provided with head and tail frame extensions 5 and 6 and a main supporting plane or surface 7 which may have any suitable lifting and sustaining curvature, and which is coextensive in area with the horizontal area of said frame structure. The tail frame 6 carries a vertical rudder 8 and an elevator or horizontal rudder 9, serving also as a tail piece, which rudders, together with the other parts of the apparatus, are adapted to be adjusted from a suitable control device within the car 1, as hereinafter fully described.

Arranged at a point centrally of the height of the upright frame 3, and equidistantly between the car 1 and supporting surface 7, are normally horizontal laterally extending wings 10 and 11 corresponding in size and construction. These wings act as supplementary supporting surfaces and have their inner edges 12 pivoted to swing vertically on axes 13. These wings are also adjustable from the control device as herein-after clearly explained.

The aviator's seat 14 is suitably mounted within the car 1, in proximity to which is arranged the control device 15, and arranged in the car in advance of said seat and control device is a pair of separate and independent driving motors 16 and 17 of corresponding working power. These motors are placed opposite each other and their shafts are respectively connected by chains 18 and 19 with sprocket wheels 20 and 21 loosely mounted on a drive shaft or countershaft 22, which sprockets are provided with friction clutch members 23 and 24 adapted for engagement with fixed clutch members 25 and 26 keyed to the shaft, through the medium of suitable controlling devices, (not shown), whereby the drive shaft or countershaft may be driven from either one or both motors at will.

The shaft 22 is journaled in bearings on the frame in the plane of the frame extensions 5 and 6, and in the upper portion of the frame, and between the horizontal center of said frame and the surface 7, are arranged suitable panels or vertical stability surfaces 26. On the head frame extension 5 are provided bearings for a horizontal transverse shaft 27 driven from the shaft 22 by sprocket chains 28 and 29. The shaft 27 supports a pair of forward rotatable prop-

ling and lifting planes or wings 30 and 31, arranged on opposite sides of the longitudinal center of the machine, each of said rotatable wings comprising a pair of parallel frame bars 32 fixed to the shaft and a pair of substantially flat blades or planes 33 disposed in diametrically opposite relation. The blades or planes 33 are fixed to front and rear shafts 34 which are journaled in 10 the frame bars 32 and provided at their inner ends with sprocket gears 35 connected by chains 36 with sprocket pinions 37, the pinions 37 associated with each rotatable wing being integral or joined for conjoint 15 rotation, and the pinion 37 of the respective rotatable wings being fixed to sleeves or hollow shafts 38 and 39 loosely mounted on the shaft 27.

It will be understood from the foregoing 20 description that in the revolution of the driving shaft 27 both rotary propelling and sustaining wings 30 and 31 will be operated, at the same rate of speed, and that in the rotation of said wings the blades or planes 25 thereof will have a combined lifting and propelling effect. The blades of each rotary wing are set at right angles to each other so that on their downward and forward or propelling motion they will lie horizontally 30 and exert a broadside lifting and propelling thrust, while on the rearward and upward or return motion they will continue to exert a lifting and propelling thrust and finally move vertically edgewise upward through 35 the air to diminish their resistance. The said blades 33 are adjustable, simultaneously or independently through the sprocket gearing described, from the sleeves 38 and 39, so that their working angles of incidence 40 may be varied to correspondingly vary their lifting and propelling action and to enable the rotary propelling and lifting devices to be employed for a variety of lifting, sustaining, steering and balancing actions in an 45 obvious manner. As shown, the ratio of the gears 37—35 is one to two, and it will be apparent that on each complete revolution of each wing, through the shifting of the chains 36 about the sprockets 37, the blades or 50 planes of the wing will feather or make a half revolution on their axes, the under surface of each blade on one revolution becoming the upper surface of the blade in the next revolution, and alternating in this manner in the successive revolutions of the wing. By turning the sleeves 38 and 39, the blades 55 may set at such angles relative to their orbit of movement that they will exert a continuous lifting force, a continuous forward pull 60 or a continuous backward pull, and hence by proper adjustments of the blades to different angles any desired lifting, propelling, stabilizing or controlling action may be effected, while by adjusting the blades of the 65 two rotary propelling and lifting devices to

different relative angles the said propelling and lifting devices may be employed for direct lifting and propelling actions, to assist in banking and steering the machine, and to enable the machine to be laterally balanced 70 under abnormal conditions and controlled under all conditions of service to a highly efficient degree.

Arranged on opposite sides of the longitudinal center of the machine, in the plane of the horizontal center of the frame 3, and beneath the lateral extremities of the main plane 7, at an elevation equidistant between the car 1 and surface 7, are rear revolving wings 40 and 41, operating as supplementary sustaining and lifting surfaces. Each of these revolving wings comprises a pair of frame bars 42 fixed to the shaft 22, and a pair of blades 43 and 44 carried by each set of frame arms, said blades being mounted on diametrically opposite sides of the shaft 22 on shafts or axes 45 journaled in the bars 42. Each blade or plane 43 44 comprises an openwork frame 45' over the top of which is stretched a body of screen material, 80 such as woven or strung wires 46, upon which frame are pivotally mounted rows of shutters or valves 47, the shutters of each row being provided with crank arms 48 connected by a link 49 coupled to the frame by 85 a controlling spring 50. The shutters are adapted to be normally held closed up against the body of screen material by the action of the springs, and in the rotation of the plane or blade are adapted to be held by 90 the springs and pressure of the air closed on their working motion to provide a solid surface to act on the air, while on the return motion of the blade or plane the shutters are adapted to open under the pressure of the 95 air from above to diminish their resistance. The inner ends of the shafts 45 are provided with sprocket gears 51 connected by chains 52 with gears 53 on sleeves or hollow shafts 54 and 55 loosely mounted on the shaft 22, 100 whereby through adjustments of said sleeves or hollow shafts the shafts 45 may be turned and the planes or blades adjusted to assume different angular working positions, enabling the lifting action of the planes or 105 blades to be varied on their revolving motions, so that the surfaces of the revolving wings may be set to exert their forces in any desired direction, upward, forward or backward, in the same direction, or to adapt the 110 revolving wings at opposite sides of the machine to have different actions for lifting, steering, banking and controlling effects, whereby the efficiency of operation of the machine and its capability of ready control 115 is further increased. The ratio of the gears 51—53 is one to one, so that the blades or planes 44 will have, in the shifting of the sprocket chains 52 in their rotation, broadside upward and downward motions, or 120

broadside downward and return motions, and edgewise movements between such motions.

In the practical operation it will be understood that the front rotary propelling and lifting devices or planes would be so adjusted as to exert principally a propelling force, in which adjustment their rotary revolutionary motions would send the air whirling backward and slightly upward against horizontal surfaces of the downwardly moving central rotary wings, which would be adjusted to chiefly produce a lifting force, thus securing first a propelling force and second a lifting force from the same air.

The sprocket chains 56 and 57 pass around sprocket wheels 58 fixed to the sleeves 38 and 39 and double sprocket wheels 59 fixed to the sleeves 54 and 55, whereby each pair of sleeves 38 and 54 or 39 and 55 may be adjusted in unison. As shown in Figs. 8 and 9, the sets of sprocket gearing connecting each sleeve with the axes of the associated blades or planes of the respective rotary propelling and lifting devices, or rotary sustaining and lifting wings, are inclosed so as to be protected from dirt, dust and injury, the sprocket wheels being disposed in suitable casings 60 coupled by right and left hand threaded tubes 61 forming guides for the sprocket chains, the said casings being provided with detachable side plates 62, allowing the sprocket gears to be readily applied and removed and the parts of the gearing to be readily cleaned, assembled and disassembled. The tubes furthermore are adapted to perform the function of turn buckles, whereby any slack in the chains may be conveniently taken up.

It will be understood that by inclosing the controlling sprocket chains 51, 52, etc., in tubes, safety is secured, as the chains will be prevented from being thrown off the sprocket wheels by the motion or velocity required.

The wings 10 and 11 are provided with openings 63 controlled by sliding shutters 64, and to the inner and outer ends of the shutter of each wing are respectively attached cords or cables 65 and 66, the cords 65 passing from beneath the shutter upwardly around a pulley 67, then across the top of the shutter and over a pulley 68 and thence downwardly and fixed at its opposite end to the frame as at 69, while the cord or cable 66 is attached at one end to the outer end of the shutter thence passes upwardly through an opening in the wing and over a pulley 68, and thence inwardly above the shutter, and is finally fastened at its opposite end to the frame, as at 69. By means of these cables, it will be evident that shifting devices are provided for sliding the shutter in opposite directions when the wing 65 is moved downwardly or upwardly from a

normal position, to control the openings 63, whereby the effective extent of service of the wing is varied as required for balancing actions. The two wings are connected for movements in unison by front and rear cables 70 and 71, respectively which pass over suitable sets of guide pulleys 72 and 73, the arrangement being such that one wing is permitted to have free downward movement and the other a corresponding upward movement, and vice versa.

The controlling device 15 comprises a lever 74 universally jointed as at 75, to a horizontal transverse rock shaft 76, said lever being movable in a fore-and-aft direction with the shaft and laterally independently of the shaft. Cords or cables 77 are connected at their forward ends with the lever above and below the universal joint, and thence pass over suitable guide pulleys 78 and are properly coupled to the horizontal rudder or elevator 9, whereby said rudder may be adjusted. Similar cords or cables 79 are connected at one end with the lever and pass over suitable guide pulleys 80 and are connected at their outer ends with the outer lateral extremities of the wings 10 and 11; whereby said wings may be simultaneously adjusted in different directions, in the adjustments of which wings the shutters controlling the openings therein are also adjusted through the shifting connections previously described. It is, of course, understood that the wings 10 and 11 are adjusted through lateral movements of the lever 74, and that through the medium of said lever, which is adjustable with its supporting shaft 76 in a fore-and-aft direction, and on the universal joint 75 in a transverse direction, as well as at different intermediate angles to such planes of motion, a combination of movements of the lever may be obtained for vertical steering and lateral balancing operations.

A hand wheel 80 is revolvably mounted on the lever 74 and provided with a drum to which are attached the forward ends of a pair of cables 81, which are adapted to wind in opposite directions upon the drum, and which are attached at their rear ends to the vertical rudder 8, whereby said rudder may be adjusted. The lever 74 also supports an auxiliary lever 82 having branching laterally arms 83 and 84, and suitably supported upon the lever 74 below said auxiliary lever are drums 85 and 86. The pulleys 59 are engaged by chain sections 87 and 88, and to the ends of the chain sections 87 are attached cords or cables 89 and 90, while to the ends of the chain section 88 are attached cords or cables 91 and 92. The opposite ends of the cables 89 and 91 are adapted to wind in the same direction upon the pulley 85, while the opposite ends of the cables 90 and 92 are adapted to wind in the same direction upon 130

the pulley 86, from which it will be apparent that when the lever 82 is adjusted in one direction, the pulleys 59 will be moved in a forward direction simultaneously, while when said auxiliary lever is moved in the opposite direction the pulleys 59 will be moved rearwardly simultaneously. By this means motion may be communicated to the chains 56 and 57 to adjust the rotary lifting 10 and propelling wings and the rotary sustaining and lifting wings for the purposes hereinbefore stated, it being understood that when the lever 74 is moved in a fore-and-aft direction the lever 82 will move with it 15 without drawing on the connections leading to the chains 87 and 88, and that when the lever 74 is moved transversely the lever 82 is left free so as to avoid drawing upon the chain connections 87 and 88. It is apparent, 20 however, that the system of control may be varied within a province of the invention to adjust the rotary wings 30 and 31, 40 and 41 in such manner as to give the wings at opposite sides of the longitudinal center of 25 the machine adjusting inclination in opposite directions, while the wings at the same side of the machine are adjusted in the same direction.

It will of course be understood that the 30 lever 74 may be properly weighted to act as a pendulum lever controlled by the force of gravity, so that an automatic controlling action of the lever may be established.

From the foregoing description, it will be 35 seen that the invention provides a flying machine in which the lifting action of the main plane is supplemented by the lifting and sustaining actions of the rotary wings, and that therefore great lifting power is secured, and 40 it will also be seen that the adjustment of the rotary wings allows the machine to be launched and caused to ascend or descend substantially in a straight path, as well as to enable the machine to be controlled at all 45 times with greater efficiency to direct it in its course of flight and to maintain longitudinal stability. More reliable and efficient lateral control is also afforded by the construction of the wings 10 and 11 and their

mode of adjustment and the use of the shutters coöperating therewith. 50

It will of course be manifest that the propelling devices may be driven from either one or both motors, thus insuring safety and continuity of flight or the making of safe 55 landings in the event of the derangement of either motor, as the other motor may be maintained in action to give the requisite driving power.

I claim:—

1. A flying machine including a main frame, a supporting surface carried thereby, rotary lifting and propelling wings arranged in advance of said supporting surface and on opposite sides of the longitudinal center of the machine, correspondingly arranged rotary lifting and sustaining wings disposed beneath the main plane and in rear of the first-named wings, each of said wings embodying blades adjustable to different 70 working angles, controlling connections for adjusting said blades, and drive gearing for simultaneously actuating said wings. 60

2. A flying machine including a main frame, a supporting surface carried thereby, 75 rotary lifting and propelling wings arranged in advance of said surface on opposite sides of the longitudinal center of the machine, each of said wings embodying blades adjustable to different working angles, gearing for adjusting said blades, correspondingly arranged rotary lifting and sustaining wings arranged beneath the supporting surface in rear of the aforesaid wings, and each of said second-named wings 85 embodying blades adjustable to different working angles, gearing for adjusting said blades, gearing for adjusting the first-named sets of gearing for effecting the adjustments of the blades of the sets of wings in unison, 90 means for controlling the last-named gearing, and means for driving the wings. 80

In testimony whereof I affix my signature in presence of two witnesses.

WELMAN B. McCARLEY.
